UNITED STATES PATENT OFFICE.

HENRY V. YOWELL, OF EL RENO, OKLAHOMA, ASSIGNOR OF ONE-HALF TO SARAH A. GARRITY, OF EL RENO, OKLAHOMA.

MUD RING FOR BOILERS.

Application filed April 6, 1920. Serial No. 371,645.

To all whom it may concern:

Be it known that I, HENRY V. YOWELL, a citizen of the United States, residing at El Reno, in the county of Canadian and State 5 of Oklahoma, have invented new and useful Improvements in Mud Rings for Boilers, of which the following is a specification.

The object of my present invention is to provide a peculiar and advantageous mud 10 ring construction of such character that mud and scale will be washed out of a boiler when the same is under steam pressure.

To the attainment of the foregoing, the invention consists in the improvement as 15 hereinafter described and definitely claimed.

In the accompanying drawings, hereby made a part hereof:

Figure 1 is a longitudinal central vertical section of the construction constituting the 20 best practical embodiment of my invention 20 of which I am cognizant.

Figure 2 is a longitudinal central horizontal section of the construction, looking downwardly.

Figure 3 is a vertical central transverse section of the construction taken in the plane indicated by the line 3—3 of Figure 1.

Figure 4 is a similar view taken in the 30 plane indicated by the line 4—4 of Figure 1.

Figure 5 is a detail, enlarged section taken in a plane immediately above one of the stretches of the mud ring.

Figures 6 and 7 are enlarged detail sections taken in the planes indicated by the lines 6—6 and 7—7, respectively, of Figure 5.

Similar numerals of reference designate 40 corresponding parts in all of the views of the drawings.

Among other elements my novel construction includes two pipes 1 and 2. The upper pipe 1 is arranged on the top of the crowning- 45 sheet 3 of the boiler for the purpose of washing off any mud or scale which may settle there; it being understood in this connection that the said pipe 1 is provided at its under side at intervals of its length with apertures 4. The lower pipe 2 is disposed in the barrel 5 of the boiler, and is designed to wash mud and scale out of the barrel and toward the blow-off valve, indicated by 6. The lower pipe 2 is also pro- 50 vided in its under side with apertures 7,

and both pipes 1 and 2 are disposed longitudinally of the boiler. At 8 the lower pipe 2 is provided with an arm that extends to the outside of the boiler, as shown.

Located between and connected by rivets 60 to the boiler sheets at the lower ends of the legs 9, is the mud ring 10 of my improvement; the said mud ring 10 being provided at 11 with an inlet for water. As shown, the pipes 1 and 2 and the mud ring 10 are 65 connected through pipes to a feed water pump 12, the said pump being designed to force feed water into the boiler through the pipe shown.

The mud ring 10 is in the form of a hollow body of sufficient size and strength for interposition between and connection to the boiler sheets. In its upper wall, the mud ring 10 is provided at intervals with apertures 13 over which are deflecting caps 14, 70 disposed as shown, in order to insure the flow of water inside the lower portion of the boiler toward the blow-off valve 6, this in order to wash all mud or scale that settle on the mud ring 10 toward the blow-off 75 valve 6, so that when the valve 6 is opened, the foreign substances will be discharged from the boiler.

It will be apparent from the foregoing 80 that when a boiler is equipped with my improvement, mud and scale may be washed out of the boiler when the same is under steam pressure, by the forcing of the water through the mud ring 10 and the pipes 1 and 2, thereby setting up a circulation of water 85 toward the blow-off valve 6, with the result that when said valve is opened, the boiler will be expeditiously and thoroughly 90 cleaned. It will also be apparent that the arrangement of my improvement is such as 95 to bring about agitation of mud or scale in the boiler, and all circulation of water being in the direction of the blow-off valve when the same is opened, the mud and scale will settle toward the said blow-off valve. In 100 this connection it will be appreciated that the mud and scale, because of their specific gravity, will be washed along the bottom of the boiler formed by the mud ring 10, until the foreign substances arrive at the blow-off 105 valve 6, which valve will be opened during the maintenance of the circulation stated.

The feed water pump 12 is connected by pipe 31 with an appropriate source of feed water supply (not shown), and by a pipe 31* 110

with the steam dome of the boiler, and by pipes 32 with the pipes 1 and 2 and the mud ring 10. The valve of the pump 12 is designated by 30, and when said valve and the 5 valve 6 are opened water will be caused to pass through the pipes 1 and 2, the interior of the boiler, the mud ring 10 and the valve 6.

Having described my invention, what I 10 claim and desire to secure by Letters-Patent, is:

1. The combination with a locomotive boiler, of a hollow mud ring interposed between and connected to the boiler sheets at 15 the bottom of the legs and having apertures in its upper wall in communication with the interior of the legs and also having above said apertures caps disposed to assist in the passage of water toward a blow-off valve 20 connected to one leg at a point slightly above the mud ring, and means for causing water to pass through the mud ring.

2. The combination with a locomotive boiler legs, of a hollow mud ring at the 25 bottom of the boiler legs, and having apertures in communication with the interior of the legs and also having caps opposite

said apertures, means for causing water to pass through said ring and a blow-off valve connected with the interior of one leg of the 30 boiler at a point above the mud ring.

3. The combination with a locomotive boiler and a blow-off valve connected with the interior of the boiler, of a hollow mud ring interposed between and connected to 35 the boiler sheets at the bottom of the legs and having apertures in its outer wall in communication with the interior of the legs and also having caps disposed above said apertures and arranged to promote the circulation of water and the movement of mud 40 and scale on the mud ring and toward the said blow-off valve, and means for causing water to pass through said ring.

4. The combination with a locomotive boiler, of an apertured mud ring connected with the legs of the boiler, a blow off valve connected with the interior of one leg of the boiler above the mud ring, and a pump connected to the mud ring.

In testimony whereof I affix my signature.

HENRY V. YOWELL.
